UNITED STATES PATENT OFFICE.

GEORGE W. NISTLE, OF MUSKEGON, MICHIGAN, AND ROBERT L. GIFFORD, OF CHICAGO,
ILLINOIS.

FLUID-CIRCULATING APPARATUS.

971,920.

Specification of Letters Patent. Patented Oct. 4, 1910.

Application filed March 11, 1909. Serial No. 482,698.

To all whom it may concern:

Be it known that we, GEORGE W. NISTLE and ROBERT L. GIFFORD, citizens of the United States, residing, respectively, at the city of Muskegon, county of Muskegon, and State of Michigan, and at the city of Chicago, county of Cook, and State of Illinois, have invented certain new and useful Improvements in Fluid-Circulating Apparatus, of which the following is a specification.

This invention relates to improvements in apparatus for circulating motive fluid and refers more particularly to an apparatus for collecting and condensing exhaust fluid after it has been circulated through an external system, and then admitting fluid at boiler pressure to said condensed fluid to equalize the pressure on either side of the latter and permit it to reenter the boiler by its hydrostatic head.

Among the objects of the invention are to provide an apparatus of the above character whereby the exhaust fluid is first condensed and then restored to the boiler as feed supply, without the aid of a pump or other external source of pressure, and these operations carried on continuously and automatically; to provide an apparatus in which the collected exhaust fluid is condensed by surface condensation from a suitable source of supply, the latter automatically cut off at predetermined intervals and live fluid then automatically admitted at boiler pressure to the tank containing the condensed fluid whereby the pressure is equalized and the condensed exhaust permitted to reenter the boiler by gravity; to provide an apparatus of this character in which the above operations are automatically regulated by simple valve mechanisms which are in turn controlled by the exhaust fluid itself; to provide an apparatus of the character referred to in which the operations of collecting and condensing the exhaust fluid and restoring the latter to the boiler are carried on periodically at predetermined intervals without any external regulation or control.

In the present instance we have shown our apparatus for circulating motive fluids as applied to a steam heating system although it is apparent that motive fluids other than steam may be used and for purposes other than that shown in the drawings.

In the apparatus here shown Figure 1

designates diagrammatically a steam heating system equipped with our improved apparatus for carrying out our method. Fig. 2 is a horizontal sectional view taken through lines 2-2 of Fig. 1 and showing more particularly the manner of arranging the condensing coils within the tank in which the exhaust steam is collected. Fig. 3 is an enlarged detail view of the diaphragm and connected valves which regulate the admission of the live steam to the condensing tank and the cold water to the condensing coils. Fig. 4 is an enlarged sectional view of the piston valve which controls the diaphragm.

Referring to Fig. 1, 1 designates the boiler which is connected to a radiator 2 by the usual pipe 3 leading from the steam space side of the boiler. From the opposite side of the radiator is connected the exhaust pipe 4 which leads into a condensing tank or cylinder 5 mounted in any suitable manner above the water line of the boiler 1. In this exhaust pipe 4 is interposed a check valve 6 opening into the tank, for a purpose hereinafter described. The lower side of the tank 5 is provided with a depressed portion 5' to which is connected a vertically extending pipe 7 the lower end of which communicates with the boiler 1. Within this pipe 7 is interposed an ordinary check valve 8 opening into the boiler. It will thus be seen that normally the steam circulates from the steam space side of the boiler out through the radiators and back into the condensing tank 5 in the usual manner. The steam as it is condensed in the tank 5 in the manner hereinafter described collects in the lower part of the tank and in the pipe 7, but inasmuch as the hydrostatic head of the condensed exhaust is obviously much less than the boiler pressure, the check valve 8 will remain closed and the condensed steam will not be able to reenter the boiler as feed water.

As heretofore stated the exhaust steam after it has been collected in the tank 5 is first condensed, the condensing liquid cut off and live steam admitted at boiler pressure into the tank to equalize the pressure and permit the check valve 8 to open through the head of the water in the pipe 7 and tank 5.

Describing now the apparatus by which these operations are accomplished, a branch pipe 9 leads from the usual cold water sup-

ply of the building to one end of the tank 5 and is there connected to a condensing coil 10. This condensing coil is seated within the tank 5 near the upper side of the latter, 5 and is supported at one end by a rod 11 extending through the sides of the tank, and at its other end extends through and is supported by the removable end closure member 12. The outlet end of the condensing 10 coil 10 is connected to a waste pipe 13 leading to the sewer or back to the cold water supply. Within this branch pipe 9 leading from the cold water supply is introduced a globe valve 15 of well known type hereinafter more particularly described.

In order that live steam may be admitted to the condensing tank 5 to equalize the pressure, the branch steam pipe 14 is connected at one end to the main pipe 3 leading from the high pressure side of the boiler, and at its other end to the tank 5 as shown at 17. The supply of live steam to the tank from the pipe 14 is normally cut off by a globe valve 16, generally similar in construction to the valve 15 referred to. The valve disks which control the passage of water and steam through the respective pipes 9 and 14 are so connected together that when one valve is open the other will be closed. To 20 this end a flexible diaphragm 17 is mounted in the diaphragm casing 18 supported upon a suitable bracket 18' fixed to the top of the tank 5 in the present instance. To the upper side of this diaphragm 17 is connected the 25 valve stem 19 carrying at its upper end the valve disk 20 of the upper valve 16. The valve disk 22 of the lower valve 15 is similarly connected to the diaphragm by means of its stem 21. As seen more clearly in Fig. 30 these valve stems 19 and 21 work through suitable bearings or guides 19' and 20' carried respectively by the diaphragm casing 18 and the casings of the globe valves. These valve stems and connected disks are 35 so arranged that when pressure is applied to the lower side of the diaphragm 17 the valve 15 will be opened and the valve 16 closed; exactly the reverse conditions result when pressure is applied to the upper side of 40 the diaphragm. Describing now the manner of operating this diaphragm 17 so as to open and close the valves, a relatively small supply pipe 23 is connected at one end to the branch pipe 9 leading from the cold water 45 supply, and at its other end to the piston valve, designated as a whole 24. It is to be noted that the pipe 23 communicates with the cold water supply pipe 9 at a point between the inlet of the latter and its globe valve 15. 50 Accordingly the supply of water to the pipe 23 is not in any way affected by the action of the globe valve 15 referred to.

Referring now more particularly to Fig. 4 the valve 24 comprises a casing 25 provided 55 with an elongated and vertically extending

valve chamber 26. This valve chamber 26 communicates at its upper and lower ends with the supply pipe 23 by means of suitable by-passes or ducts 27, 28 respectively, and a common in-let port 29. At its opposite side 70 the valve casing 25 is provided with two outlet ports 30, 31 and a common exhaust port 32. The ports 30 and 31 are controlled respectively by closure rings 34, 35 carried by a valve piston 33 mounted to reciprocate in 75 the valve casing 25. These rings are so arranged that when the piston is near its upper limit of movement as shown in Fig. 4 the lower port 31 will communicate with the by-pass 28 and supply pipe 23, while at the same time the port 30 will be positively cut off from the upper by-pass 27 by means of its closure ring 34. Exactly the reverse conditions exist when the piston is shifted to its lower position. The middle or exhaust port 80 85 32 alternately communicates with the upper and lower ports 30 and 31 respectively and to this port is connected a waste or exhaust pipe 37. In order to cushion the stroke of the piston 33 the port 31 is set above the inlet of the by-pass 28 so that part of the water in the lower end of the chamber will be trapped upon the descent of the piston and serve to cushion the stroke of the latter. The piston valve is connected with the diaphragm casing as follows: To the upper port 90 95 30 is connected a pipe 39 which leads to and communicates with the upper side of the diaphragm 17 while in the same manner a similar pipe 40 communicates at one end with the port 31 and at its other end with the lower side of the diaphragm.

From the foregoing it will be seen that when communication is established between the port 31 and the by-pass 28 pressure will be admitted to the lower side of the diaphragm 17 through the pipe 40; while at the same time the upper port 30 will be cut off from the by-pass 27 and opened to the exhaust port 32. Accordingly the valve stems will be shifted upwardly, the valve 15 opened and the corresponding valve 16 closed. When the piston is shifted in the opposite direction exactly the reverse conditions result pressure being admitted to the upper side of the diaphragm and removed from the lower side thereof. The condensing water and the live steam will thus be alternately admitted to and cut off from the tank 5.

Describing now the manner of operating the piston 33, extending transversely of the condensing tank 5 near one end thereof is rotatably journaled a rock shaft 41, to which is connected a float 42 by means of a stem 43. One end of this rock shaft 41 extends through the side of the tank as shown more clearly in Fig. 2 and to this extension of the shaft is rigidly connected a rocking lever 44. The free end of this lever arm 44 is provided 110 115 120 125 130 with a laterally projecting stud 45 which

rides within a link 46 mounted upon the upper end of the stem of the piston 33. The connection between the lever arm 44 and the link 45 is in effect a lost motion connection, 5 so that the piston will be actuated only when the lever arm 44 is approximately at its limit of movement in either direction. In other words during the greater part of the movement of the float the stud 45 will ride 10 loosely in the link 46 and will only actuate the latter as the float reaches its limit of movement in either direction. The manner of operating the piston 33 is apparent from the above description. Before the condensed 15 exhaust steam has accumulated in the bottom of the tank the float will, of course, be down and the piston rod raised to the position shown in Fig. 4. At this time the pipe 40 leading to the lower side of the diaphragm 20 is in communication with the supply pipe 23, the valve 15 is open and the corresponding valve 16 closed as heretofore described. As the water of condensation accumulates in the pipe 7 and tank 5 the float 42 will gradually 25 rise, and as it approaches its upper limit of movement the stud 45 will engage the lower end of the link 46 and shift the piston downwardly. This cuts off the supply of water to the pipe 40 and opens the latter to the ex- 30 haust 37. The pressure on the lower side of the diaphragm is accordingly removed. At the same time communication is established between the supply pipe 23 and the pipe 39 leading to the upper side of the diaphragm 35 whereupon the valve stems 19 and 21 are shifted downwardly, the valve 15 closed and the valve 16 opened. Live steam now rushes into the condensing tank 5 through the branch pipe 14 and equalizes the pressure 40 upon opposite sides of the water of condensation in the tank. The check valve 6 interposed in the exhaust pipe 4 will, of course, prevent the live steam from backing up against the exhaust and inasmuch as the 45 pressure on the opposite sides of the water of condensation is equalized the latter will by gravity open the check valve 8 and re-enter the boiler as feed water.

The operation of the apparatus shown will 50 be apparent from the foregoing description and need not therefore be described in detail. However, it is to be particularly noted that the various operations of our methods are carried on continuously and automatically; 55 that the various valve mechanisms have simple and positive actions and that the intervals at which live steam may be admitted to the tank may be easily regulated by adjusting the leverage mechanism which controls 60 the piston valve 24.

We claim as our invention:

1. The combination with a motive fluid system, of a boiler for supplying fluid to said system, a condensing tank connected to 65 the exhaust side of said system and having

its lower side elevated above the bottom of the boiler, a condensing coil seated in said tank and connected to an external source of cold fluid, a conduit connecting the boiler with said tank to supply the latter with live 70 fluid, valve mechanism regulating the supply of cold liquid to said condensing coil, and the supply of live fluid to the tank, means controlling the operation of said valve mechanism and a conduit connecting the 75 tank to the boiler to permit the condensed exhaust fluid to reenter the latter, and normally closed valve mechanism interposed in said conduit.

2. In a fluid-circulating apparatus, the 80 combination of a boiler, a circulating system external to the boiler, a condensing tank connected to the return side of said system, surface condensing apparatus for subjecting the steam in said condensing tank to the action of a condensing medium, means for intermittently interrupting the action of said condensing medium, connections for conducting live steam substantially at boiler pressure to said condensing tank, a conduit 85 connecting the lower part of said tank with said boiler, and automatic valve mechanism controlling the admission of live steam to said condensing tank.

3. In a fluid-circulating apparatus, the 90 combination of a boiler, a circulating system external to the boiler, a condensing tank connected to the return side of said system, surface condensing apparatus for subjecting the steam in said condensing tank to the action of a condensing medium, means for intermittently interrupting the action of said condensing medium, connections for conducting live steam substantially at boiler pressure to said condensing tank, a conduit 95 connecting the lower part of said tank with said boiler, automatic valve mechanism controlling the admission of live steam to said condensing tank, automatic valve mechanism controlling the flow of condensing medium, and means operated by the accumulation of water of condensation for controlling both of said automatic valve mechanisms.

4. The combination with a motive fluid 110 system, of a boiler for supplying live fluid to said system, a condensing tank connected to the exhaust side of said system, and having its lower side elevated above the bottom of said boiler, a condensing coil seated in 115 said tank and connected to an external source of condensing fluid, means for supplying fluid at substantially boiler pressure to said tank, automatically controlled valve mechanism regulating the supply of condensing fluid to said coil and the supply of live fluid to said tank, and a conduit connecting said tank to the boiler and normally closed valve mechanism interposed in said conduit.

5. In a fluid-circulating apparatus, the 120

- combination of a boiler, a closed circulating system external to the boiler, a condensing tank connected to the return side of said system, a closed surface condensing coil arranged within said tank, valve mechanism for controlling the flow of condensing medium through said coil, connections for conducting live steam substantially at boiler pressure to said condensing tank, valve mechanism controlling said connections, a conduit connecting the lower part of said tank with said boiler, valve mechanism controlling said conduit, a source of power, independent of the hydrostatic head of collected water of condensation, for actuating said first two valve mechanisms, and means actuated by the accumulation of water of condensation in said tank for controlling said source of power.
6. In a fluid-circulating apparatus, the combination of a boiler, a closed circulating system external to the boiler, a condensing tank connected to the return side of said system, a closed surface condensing coil arranged within said tank, valve mechanism for controlling the flow of condensing me-
- dium through said coil, connections for conducting live steam substantially at boiler pressure to said condensing tank, valve mechanism controlling said connections, a conduit connecting the lower part of said tank with said boiler, valve mechanism controlling said conduit, a source of power, independent of the hydrostatic head of collected water of condensation, for actuating said first two valve mechanisms, and means actuated by the accumulation of water of condensation in said tank for controlling said source of power, said valve-actuating mechanism embodying means whereby the several valves are actuated in definite timed relation.
